UNITED STATES PATENT OFFICE.

WILLIAM B. BULL, OF QUINCY, ILLINOIS.

ELECTRIC INCRUSTATION-PREVENTER.

SPECIFICATION forming part of Letters Patent No. 430,462, dated June 17, 1890.

Application filed March 12, 1890. Serial No. 343,633. (No model.)

To all whom it may concern:

Be it known that I, WILLIAM B. BULL, of Quincy, in the county of Adams and State of Illinois, have invented certain new and useful Improvements in Magnetic Purifiers and Incrustation-Preventers for Steam-Boilers; and I do hereby declare the following to be a full, clear, and exact description of the same, reference being had to the accompanying drawings, forming a part of this specification, and to the letters of reference marked thereon.

This invention relates generally to that class of devices for purifying liquids or preventing boiler incrustation in which the liquid is subjected to the influence of a magnet, and more particularly to that class in which the water on its way to the boiler or reservoir is passed through a magnetic field, whereby the impurities are removed or so altered as to relieve them of their harmful properties, the exact nature of the changes being, so far as I am at present aware, unknown, although the results are well-established facts and need not be further mentioned at this time.

The object of the invention is to simplify the apparatus necessarily employed, adapting it for application to feed-pipes or liquid-conduits of any character, whether of magnetic or non-magnetic material, although the former is preferred, and, further, to reduce the cost of the apparatus to the minimum.

Broadly stated, the invention may be said to consist in locating a magnet within and independent of the conduit, and in a further development of this idea consisting in employing a series of magnets arranged in a bundle or sheaf to act on the liquid at one time, or distributed along the conduit so as to act in succession.

The invention further consists in certain novel details of construction and combinations and arrangements of parts to be hereinafter described, and pointed out particularly in the claims at the end of this specification.

Referring to the accompanying drawings, Figure 1 is a perspective view of a section of a conduit with a portion broken away to show the interior arrangement. Fig. 2 is a cross-section. Fig. 3 is a longitudinal section showing one arrangement of magnets for acting

successively. Fig. 4 is a perspective view similar to Fig. 1, showing a modification. Fig. 5 is a cross-section of the same. Fig. 6 is a perspective view of a bundle of prismatic magnets which may be used. Fig. 7 is a cross-section showing the prismatic magnets in position. Fig. 8 is a view similar to Fig. 3, showing a series of sheafs of magnets.

Like letters of reference in the several figures indicate the same parts.

Various attempts have heretofore been made to produce an apparatus of this character which could be readily applied to conduits or feed-pipes now in use without any material alteration in the same or the necessary supports and surroundings, and it must be admitted that more or less success has crowned these efforts; but difficulty has been experienced in getting the maximum effect of the magnets or the most intense magnetic field within the conduit, either because of the remoteness of the magnets themselves from the center of the conduit and liquid passing through the same, thereby reducing the intensity of the magnetic field in an enormous ratio, or because of the faulty construction and application of the magnets, which prevented the formation of true poles or magnetic centers in the most advantageous positions because of the dissipating influence of the walls of the conduit itself, owing to the contact of the magnet or magnets therewith. My invention in a measure overcomes these difficulties in a manner to be now pointed out.

A indicates the pipe or conduit through which the liquid to be purified passes, and within this conduit is located a magnet or magnets supported by suitable spiders, studs, or open-work frames, and preferably having their poles arranged longitudinally of the conduit.

In Figs. 1, 2, and 3 the magnets are shown as cylindrical magnets B, located within a short section of the conduit, which, for convenience and to prevent any retardation of the liquid, is preferably made somewhat larger than the other portion of the conduit, the magnets being supported entirely out of contact with the walls of the conduit by studs or arms b, of non-magnetic material, if desired, thus permitting of the ready passage of the water around and, if the magnet be tubular, through

the same close to the magnetic poles, and therefore through the most intense magnetic fields. When desired, the magnets may be arranged, as in Fig. 3, one behind the other, with opposite poles in proximity and a small space between their adjacent poles, or a bracket or arm *b*, of non-magnetic material, may connect the poles to form a rigid structure.

The effect of locating the magnets within the conduit and out of contact with the wall of the same when of magnetic material, it will be seen, is to induce magnetic conditions in the conduit itself and establish an intense magnetic field between the two similar to that established between magnets of opposite polarity when brought into juxtaposition, and through this field or fields the liquid is caused to pass. If more than one magnet is employed, as in Fig. 3, the liquid is subjected to the influence of a series of magnetic fields, insuring a complete effect on all of the water passing through the same.

Where the conduit is large or it is desired to subject the water to the action of the magnetic field for a longer period of time by passing the same through a chamber of very much larger cross-sectional area than the conduit a series, bundle, or sheaf of magnets may be located within the conduit or chamber with relatively small spaces between the poles of the magnets, adjacent poles of course being preferably of opposite polarity, so as to intensify the magnetic field.

The preferred arrangements of magnets when a number is employed is shown in Figs. 4 to 7, inclusive. In Figs. 4 and 5 the magnets *E* are cylindrical in cross-section, and are so arranged as that but very small spaces are left between any two magnetic points, the collective area or capacity, however, being made equal to or greater than that of the conduit on either side of the magnets, to prevent any retardation or permit the water to remain longer within the magnetic field. The cylindrical sheaf of magnets, it will be seen, is held in place by an open frame-work *E'*, preferably of non-magnetic material, and the whole sheaf and frames are preferably so joined as that they may be readily removed in a body from the conduit. In fact, all of the forms of the invention preferably embody this feature.

A more economical and perhaps more convenient form of the device is illustrated in Figs. 6 and 7, wherein a series of prismatic magnets *G* is provided, joined together by bolts and intermediate washers *g'g*.

The magnets are properly proportioned and arranged, with the widest at the middle and gradually narrowing as they near the sides to fit within a tubular conduit or chamber, leaving a series of slits or flat openings for the passage of the water. This form of the sheaf or bundle of magnets may be held in place by arms *H*, secured in place by the bolts and adapted to rest against the sides of the conduit.

While I have specifically described the magnets as being located within a chamber of larger capacity than the conduit, I do not wish to be limited absolutely thereto, as in many instances the magnets may be suspended directly in the conduit without changing the same at all, save to disconnect a joint and slip the magnets in place. Neither do I wish to be limited to any particular form of magnet or magnets, nor to placing but a single sheaf of magnets within the conduit, as a series of sheafs may be located therein, as shown in Fig. 8.

The device may be, and, as shown, is, especially designed to be employed as an incrustation-preventer for steam-boilers, in which instance it is located within the feed-pipe; but it is obvious that it may be employed for other purposes, as the aging of liquors, &c., and therefore I do not wish to be limited to any special application, intending it for use wherever it may be desirable to subject a body of liquid passing through a conduit to a magnetic action for the removal of impurities, &c.

Having thus described my invention, what I claim as new is—

1. In a magnetic purifier for liquids, the combination, with the conduit or passage through which the liquid passes, of a magnet located entirely within said conduit, substantially as described.

2. In a magnetic purifier for liquids, the combination, with the conduit or passage through which the liquid passes, of a magnet located within and out of contact with the walls thereof, substantially as described.

3. In a magnetic purifier for liquids, the combination, with the conduit or passage through which the liquid passes, of a magnet removably suspended in said conduit and out of contact with the walls thereof, substantially as described.

4. In a magnetic purifier for liquids, the combination, with the conduit or passage through which the liquid passes, of the series of magnets arranged in proximity to each other and having adjacent poles of opposite polarity, substantially as described.

5. In a magnetic purifier for liquids, the combination, with the conduit or passage through which the liquid passes, of a magnet suspended within the same and having its poles arranged longitudinally thereof, whereby the liquid is subjected to the successive action of two magnetic fields of opposite polarity, substantially as described.

6. In a magnetic purifier for liquids, the combination, with the conduit or passage through which the liquid passes, of a series of magnets interposed therein to act on the water successively with their proximate poles of opposite polarity, substantially as described.

7. In a magnetic purifier for liquids, the combination, with the conduit through which the liquid passes, of a series of magnets con-

nected together and removably secured within the conduit, substantially as described.

8. In a magnetic purifier for liquids, the combination, with the conduit through which the liquid passes, of a series of substantially parallel magnets suspended within the conduit, with their poles arranged longitudinally of the conduit, substantially as described.

9. In a magnetic purifier for liquids, the combination, with the conduit through which the liquid passes, of a series of parallel magnets connected together and removably secured within the conduit, substantially as described.

10. In a magnetic purifier for liquids, the combination, with the conduit through which the liquid passes, of a series of substantially parallel magnets connected together, with their proximate poles of opposite polarity and suspended within the conduit, substantially as described.
